Inventor
RAYMOND W. PAUL

By

Chas. Farren, Attorney

UNITED STATES PATENT OFFICE.

RAYMOND W. PAUL, OF PIKE ROAD, NORTH CAROLINA.

BACKBAND.

1,423,144.

Specification of Letters Patent. Patented July 18, 1922.

Application filed July 14, 1921. Serial No. 484,748.

To all whom it may concern:

Be it known that I, RAYMOND W. PAUL, a citizen of the United States, residing at Pike Road, in the county of Beaufort and 5 State of North Carolina, have invented certain new and useful Improvements in Backbands, of which the following is a specification.

This invention relates to back bands, and 10 more particularly to back bands for plowing and other heavy work.

An object of the invention is the provision of a combined back band, trace carrier, and rein holder that is strong, durable, 15 light, economical, and comfortable for the animal.

A further object is the provision of a back band that will be free from projecting hooks, eliminating the possibility of catching a part of the harness or becoming entangled therewith.

A further object of the invention is the provision of the pads formed of soft wood and adjustably mounted on the back band 25 so that they may be moved to conform to the shape of the animal's back.

In the accompanying drawings, I have shown one embodiment of the invention. In this showing:

30 Figure 1 is a perspective view,

Figure 2 is a side elevation of the trace carrier and rein holder, and,

Figure 3 is a vertical sectional view on line 3—3 of Figure 2.

35 Referring to the drawings, the reference numeral 1 designates an inverted V-shaped metal band adapted to fit over the back of the animal. Adjacent each end, the band is provided with a plurality of openings 2.

40 Pads 3 are adapted to be secured to the band by means of suitable fastening elements 4 arranged in one of the openings. The pads are preferably made of soft wood, and are provided with an even surface to bear

45 equally upon all parts of the animal. As shown, the corners of the pads are rounded, as at 5, and slightly bevelled to eliminate sharp edges which may cause chafing. The pads are recessed for the reception of the

50 metal band and the surface of the band is arranged flush with the surface of the pad. An inturned hook 6 is arranged on each end of the band.

A chain 7 is adapted to be secured in each 55 of these hooks, the chain being provided with a ring 8 at the lower end.

The trace carrier and rein holder consists of a block 9, similar in construction and formation to the pads 3, the block being provided with a metal guide member 10. As 60 shown, the guide member is secured to the block by screws 11 and 12, one of which extends through the outer wall 13 of the metal member. The lower portion of the metal member is provided with a pair of 65 parallel walls for the reception of the trace chain, the outer wall being offset, as at 14, to form a restricted lower portion 15 in which the chain 16 is arranged. The upper portion of the metal member is formed sub- 70 stantially circular in shape, as at 17, and is adapted to receive the ring 8. A roller 18 is arranged on the screw 12 at the bottom of the circular portion 17 and the reins are adapted to pass over this roller. 75

The provision of pads made of soft wood is advantageous in that they are cooler than cloth pads and the provision of a smooth surface is preferable to a convex or rounded pad because of the distribution of the weight 80 on the animal's back. The inturned hook 6 and the elimination of hooks on the trace carrier and rein holder prevents any harness on the same animal, or another one, from becoming accidentally caught in the 85 back band. The reduced lower portion 15 securely retains the trace chain and prevents it from becoming accidentally free of the trace carrier. The reins, arranged over the rollers 18, work free and easily and cannot 90 become caught or jammed in any part of the harness.

It is to be understood that the form of the invention herewith shown and described are to be taken as a preferred example of the 95 same, and that various changes in the shape, size, and arrangement of parts may be resorted to without departing from the spirit of the invention or the scope of the subjoined claim.

Having thus described my invention, I 100 claim:

A back band comprising a pair of cushioning pads adapted to engage the back of a horse, said bands being provided with flat 105 engaging surfaces, and being further provided with transverse grooves in their upper faces, a substantially inverted V-shaped member, said member being provided with a plurality of openings adjacent each end 110 to permit said cushioning pads to be secured thereto in various positions, the ends of said

member being provided with inturned hooks, flexible connections secured to said inturned hooks, and a combined rein holder and trace carrier secured to the other end 5 of said connections, each of said rein holder and trace carriers comprising a block, a member secured to said block comprising a pair of spaced sides, the lower portions of said sides being arranged relatively close to 10 each other and adapted to receive a link of a trace chain, the intermediate portion thereof being relatively spaced to permit

passage of a trace chain, and the upper portion being arranged to form a substantially circular portion for the reception of a 15 rein, and a roller mounted beneath said substantially circular portion.

In testimony whereof I affix my signature in presence of two witnesses.

RAYMOND W. PAUL.
